UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

INKSTAND AND PEN FILLER

Application filed December 14, 1927. Serial No. 239,895.

My invention relates in general to ink dispensers, and has more particular reference to a mechanism used in connection with an ink container, whereby an inking pen, removably positioned within the bottle, may be raised therefrom to a position for delivering ink.

Such a device is of special utility in connection with the charging of inking instruments such as are used by draftsmen with suitable ink, and it is desirable to provide a mechanism for raising a charging instrument from position in the ink container to ink delivering position upon depressing a handle, and in order to enable an operator to more easily charge an inking instrument, it is desirable to arrange the parts in such a position that the handle depressing and instrument charging operation may be accomplished with one hand only.

20 The principal object of my invention is the provision of an instrument charging mechanism having an operating handle conveniently arranged adjacent the ink container so that upon actuation of the mechanism, an ink container may be raised from ink receiving position within the container to ink delivering position outside of the container, the mechanism being arranged so that an operation may charge an inking instrument

25 with one hand.

Another important object of the invention is the provision of interlocking means for preventing over travel of the mechanism of my present invention.

30 Still another object of the invention is the provision of a simple means for firmly securing an ink container in position in a standard upon which the mechanism of my invention is arranged.

40 Another important object of the invention is the provision of an improved, resilient inking tip, especially adapted for use in the device of my present invention.

45 Still another important object of my present invention is the provision of an interlock whereby the inking element is secured firmly in raised ink dispensing position to facilitate the delivery of ink to an instrument.

50 Numerous other objects and advantages of the invention will be apparent as it is better

understood from the following description, which, taken in connection with the accompanying drawings discloses a preferred embodiment of the invention.

Referring to the drawings:

55

Figure 1 is a plan view of an automatic inking device embodying my invention;

Figure 2 is a side view of the device, illustrated in Figure 1;

Figure 3 is an end view of the device, taken 60 from the left in Figure 1;

Figure 4 is a vertical cross section taken substantially along the line 4—4 of Figure 1, showing the inking device in raised position;

Figure 5 is a vertical cross section similar 65 to Figure 4, the parts being shown locked in raised position; and

Figure 6 is a perspective view of an improved inking tip of my invention.

To illustrate my invention I have shown 70 on the drawings an ink container 11, which, in the illustrated embodiment, is formed of glass, but which, it will be understood, may be formed of any convenient material, and have any convenient shape and size. The ink container is supported in a base 13, which carries an arm 15 and an operating lever 17, pivotally mounted therein behind the container.

75 The container 11 is mounted in a socket 19, formed in the base for the purpose of maintaining the bottle in proper relative position with respect to the arm 15, and operating lever, and is secured in place by means of a resilient clip 69 secured to an integral

80 raised portion 49 extending upwardly of the base 13 behind the socket 19. The clip is secured to the portion 49 by means of a screw 71 or other suitable fastener, and extends

85 forwardly thereof, having arms embracing the neck of the ink container. The arms are adapted to engage over the shoulders of the bottle, and, being deflected upwardly from normal position when the container is arranged in place, serve to securely clamp the 90 container in its socket.

95 The arm 15 is pivoted between spaced upstanding ridges 21, formed in the base 13 behind the raised portion 49, by means of a horizontal pivot pin 23 mounted therebe-

100

tween. The arm 15 extends forwardly of its pivot and overhangs the container, and has a hemispherical head 27, formed at its forward end, the flat surface of which is adapted to engage and close the mouth of the container 11. A socket is formed centrally of the lower flat surface of the head 27, and a rod 31, having an end 33, slotted diametrically at 35, is secured in the socket. The rod 31 has shoulders 37 of reduced diameter at each end, the lower of which is provided with screw threads 39, upon which is secured an inking tip, comprising a spiral spring 41, the upper portions of which are threaded upon the thread end of the rod. The lower end of the spring is bent to form an inking loop 43. A washer 45 is secured on the shaft adjacent the upper shoulder 37 and immediately beneath the lower surface of the head 27. This washer provides a means for sealing the ink bottle.

The arm 15 is normally urged by gravity to the container closing position shown in Figure 2, in which the lower end of the rod 31, carrying the inking tip 41, is immersed in the ink contained within the container. The arm 15 may be raised to the position shown in dotted lines in Figure 2 by means of the operating lever 17 which comprises a portion 55, pivotally mounted upon a pin 57, supported between spaced ridges 53, extending upwardly from the base 13. The spaced ridges 53 extend substantially normally to the ridges 21 between which the arm 15 is pivoted, so that the lever and arm operate in substantially normal planes. The ridges 21 have vertical front edges 47 and the rearmost of the ridges 53 extend in the plane of these edges, while the raised portion 49 has a substantially vertical rear face 51 spaced from the edges 47 and the foremost of the ridges 53 extends in the plane of this face. The operating lever 17 has a finger piece 59 extending substantially at right angles to the lever portion 55 and along the side of the base from front to rear thereof and the forward end is arranged adjacent the sides of the container, thus providing means whereby the mechanism may be operated by pressure exerted upon the finger piece 59 at any point. It will be understood that the lever portion 55 operates in the groove formed between the wall 51 and the edges 47, which are thus adapted to prevent the lever from cocking or jamming when off center pressure is exerted upon the finger piece 59 at its extremities. The lever 55 has a cut-out portion providing a detent 61 which is adapted to engage a cooperating detent 63, formed in the arm 15. These detents provide a means for limiting the movement of the arm 15, and prevent such overtravel of the device as may be occasioned by a too vigorous operation of the actuating lever 17. The lever portion 55 is provided with a flat

surface 65 adjacent the detent 61. This flattened surface is adapted to engage a cooperating flat surface formed in the cap carrier 15 in order to lock the latter in raised position as shown clearly in Figure 5 of the drawings, in order to allow the ink bottle to be removed from position in the base.

Apertures 73 are formed through the base at the socket 19 and serve to accommodate screws or other similar fastening members for securing the device in place upon a drawing board, table or other supporting device.

The device of my invention is adapted for one-handed manipulation, that is to say, a user may depress the handle 59 of the operating lever 17 with the same hand in which an inking instrument is held in position to be charged. Upon depressing the finger piece, the inking tip is raised from the bottle to a position in which an instrument held by the operator may be conveniently charged. By providing a finger piece which may be depressed at any point within the limits of the device, the individual operator may assume the most comfortable hand position, and hence charging of the instrument, which otherwise is difficult due to an unnatural or cramped hand position predicated by having a finger piece arranged at one point only, is made easy. The novel interlock provided between the lever portion 55 and the arm 15 not only prevents the arm from overtravelling but also clamps the parts in raised position and keeps the inking element from wabbling when the charging operation is attempted. Upon release of the lever 55, the large hemispherical head of the cap carrier immediately drops by gravity and the inking tip is replaced in ink receiving position within the bottle, the washer 45 providing a secure seal for the ink container.

The novel construction of the inking tip, which is shown clearly in Figure 6, provides a flexible tip for charging an inking instrument which is not subject to the disadvantages of the quill pens and other similar semi-rigid inking devices heretofore provided, which if not treated with care, become unfit for use, being easily destroyed by accidentally falling against the neck of the bottle during closing. The tip of my invention, however, being flexible, is not easily damaged by falling on a hard resisting surface, but will readily deflect and spring back to normal position. The tip, moreover, being resilient, lends itself to easy charging of the inking instruments. The shank supporting the inking tip, being slotted at its upper end, is frictionally and firmly held in the socket of the arm 15. The shank may be easily rotated by hand to dispose the plane of the inking loop in any desired direction in order to facilitate the inking operation. The shank also may be easily removed to facilitate cleaning of the parts.

It is thought that the improvements whereby the arm 15 may be propped in raised position, thereby allowing unhindered removal of the ink bottle or filling thereof in place, 5 will be readily apparent from the foregoing description.

Having thus described my invention, what I claim as new and desire to protect by Letters Patent is:—

10 1. In a device of the class described, a container, a frame for supporting it, an inking tip movably arranged within the container, means for moving said inking tip to ink delivering position and cooperating stops carried by the tip moving and tip supporting means for preventing over-travel of the tip.

15 2. In a device of the class described, a frame, an ink container supported in said frame, an inking device removably positioned within said container, a lifting arm to which said inking device is mounted, an operating member for moving said arm, said member being pivoted in said frame and having a 20 detent adapted to engage said arm to limit the 25 movement imparted thereto by said member.

30 3. In a device of the class described comprising, a frame, an ink container supported in the frame, an inking device removably positioned within the container, a pivoted arm on which said inking device is carried, a manually operable lever for moving said arm, and means in said lever adapted to engage cooperating means formed in said 35 arm to prevent over-travel thereof.

40 4. In a device of the class described including an ink container and an inking device removably positioned within said container, means for raising said inking device, a pivoted member for actuating said means and 45 co-operating means formed and arranged on said means and member to prevent over-travel of the inking device and to secure the same firmly in ink delivering position when desired.

50 5. In a device of the class described having a frame, an ink container supported in said frame and an inking device removably positioned within the container, means for raising said device to ink delivering position comprising an arm pivoted in said frame, an actuating member for said arm and means co-operating between said arm and said actuating member for preventing 55 over-travel of the former.

60 6. In a device of the class described having a frame, an ink container supported in said frame and an inking device removably positioned within the container, means for raising said device to ink delivering position comprising an arm pivoted to said frame, an actuating member for moving said arm and co-operating means arranged on said arm and said actuating member to provide 65 interlocking engagement therebetween.

to secure the inking device firmly in ink delivering position.

7. In a device of the class described having a frame, a container supported in said frame and a removable cover for said container, an arm pivoted in said frame and carrying said cover and a member for moving said arm to raise said cover, said member having a portion adapted to engage beneath said arm to hold the same in raised position. 75

8. In a device of the class described having a base, an ink container supported in said base, a removable cover thereon, and an inking device removably positioned within said container, means for raising said cover and said inking device, the inking device support means and the said means for raising same having cooperating portions adapted to engage when the inking device and the said cover are in fully raised position for 80 propelling the same in raised position. 85

9. In a device of the class described, an ink container, an inking device removably positioned within said container and comprising a shank having a threaded lower end and a spring threaded upon said lower end 90 and carrying an inking tip.

10. In a device of the class described including an ink container, an arm pivoted adjacent said container and having a portion overhanging the same, an inking device comprising a shank having an end mounted in said arm and a threaded lower end movable into and out of said container, said lower end having threaded engagement with an inking 95 loop resiliently attached thereto and adapted to assume normal position after being displaced therefrom. 100

11. In a device of the class described, an ink container, an inking device removably positioned within said container and means for raising said device to ink delivering position including a carrying arm, said device comprising an inking tip supported by a rotatably mounted rod to permit angular 105 110 adjustment of the tip.

12. In a device of the class described, an ink container, an inking device removably mounted in said container and supported in an arm, said arm being adapted to raise the device to ink delivering position, said device comprising a rod having an end frictionally engaged in a socket formed in the arm, said end being slotted axially and the parts spread to provide a rotatable and easily 115 demountable rod. 120

In witness whereof, I have hereunto subscribed my name.

ADOLPH LANGSNER.
